CLAIM

The ornamental design for a mobile television receiver module with an integrated telescoping antenna, as shown and described.

DESCRIPTION

FIG. 1 is a top view showing mobile television receiver module with an integrated telescoping antenna and a detachable cap for our new design.

FIG. 2 is a left side view thereof.

FIG. 3 is a right side view thereof.

FIG. 4 is a bottom end view thereof.

FIG. 5 is a top end view thereof with the integrated telescoping antenna retracted.

FIG. 6 is a perspective view thereof.

FIG. 7 is a top view thereof with the detachable cap removed.

FIG. 8 is a left side view thereof with the detachable cap removed.

FIG. 9 is a top view thereof with the integrated telescoping antenna retracted.

FIG. 10 is a left side view with the integrated telescoping antenna retracted; and,

FIG. 11 is a perspective view with the integrated telescoping antenna retracted.

The portions of the drawings shown in dashed lines do not form a part of the claimed design.
